UNITED STATES PATENT OFFICE.

CARL MARCH, OF CHICAGO, ILLINOIS.

CONFECTIONER'S PATTERN MARKER.

Application filed June 30, 1926. Serial No. 119,638.

My present invention has reference to a confectioner's pattern marker.

My primary object is to provide a pattern marker for confectionary bakers that includes a frame which has a widened base to rest upon a frosted cake and which has its upper edge notched, patterns being provided and being received in the frame and having headed studs which are passed into the notches of said frame, whereby said patterns are removably sustained in the frame, and each of said patterns having sharpened elements extending from the lower edge thereof, which project beyond the lower edge of the frame, and whereby when the frame and patterns are arranged upon the cake the outline of the design will be impressed on said cake, so that the baker or his apprentice may follow the impression with a regular icing tube and thereafter fill in the design with frostings which may be colored so that a highly decorated cake can be thus produced in an easy and expeditious manner and without the employment of skilled labor.

To the attainment of the above broadly stated object and others which will present themselves as the nature of the invention is better understood, the improvement further resides in certain novel features of construction, combination and operative association of parts, a satisfactory embodiment of which is disclosed by the accompanying drawings.

In the drawings:

Figure 1 is a plan view of my improvement.

Figure 2 is a sectional view on a somewhat enlarged scale taken approximately on the line 2—2 of Figure 1.

Figure 3 is an edge view of the improvement.

Figure 4 is a plan view illustrating a slight modification.

Figure 5 is an enlarged sectional view on the line 5—5 of Figure 4.

As disclosed by the drawings, I make use of a frame 1. In the showing of the drawings, the frame is in the nature of a flat ring member, but may, of course, be variously shaped. The frame has its lower edge widened, as at 2, and its upper edge provided with equidistantly spaced notches 3.

In the showing of Figures 1 and 2 I arrange in the frame partition members 4. These partition members have their outer ends, adjacent to their upper corners, provided with shanks 5 having headed ends 6.

The upper edges of each of the partitions are provided with equidistantly spaced notches 7. The confronting inner ends of the partitions may be connected together in any desired or preferred manner, and the partitions it will be noted are removably associated with the frame. As a matter-of-fact, by providing the frame with the notches the partitions may be arranged therein at various desired angles, although, as shown in Figure 1 of the drawings, all of the partitions radiate from a common center. Between the partitions I arrange patterns 8. The sides and outer end of each pattern is provided with studs 9 having heads 10, and these studs are designed to be received in the notches of the frame and in the notches of the partitions, the heads contacting with the outer faces of the frame and with the said partitions. In this manner it will be noted that the patterns may be easily but removably arranged in the frame. The patterns may be of any desired design, such as an ornamental figure, as disclosed by Figure 1 of the drawings, or the representation of the head of a human being as disclosed by Figure 4 of the drawings. In fact, floral, animal and any other shaped patterns may be employed, but the said patterns are necessarily provided with the headed studs for engaging the notches of the frame or of the partitions for supporting the same in the frame. Preferably, but not necessarily, the patterns are formed of steel spring wire, although in the showing of the drawings the said patterns are in the nature of metal strips suitably connected together. The lower edges of the patterns are all formed with equidistantly spaced pointed elements or pins 11, and these elements are designed to project beyond the widened end 2 of the frame.

In practice the frame is arranged over a cake or similar confection which has been frosted, the frosting or icing being wholly or partly dry. Thereafter when employed the partitions are positioned in the frame and supported in a manner as just described. Then the patterns are arranged in the frame. The pins or pointed elements 11 will enter the frosting on the cake and will leave an impression of the design thereon. The frame and the patterns are then removed and a baker, his apprentice or other unskilled person will, by the employment of a regular icing tube, follow the lines left by the impression

so that the design will be conveyed onto the cake. Of course, the design may be ornamented by colored frostings. The improvement is of a simple nature and will last indefinitely as there is no part thereof subject to wear or misuse.

In Figures 4 and 5 I have illustrated a further embodiment of the improvement. In these figures the frame 1' is similar to that previously described, but the design, as previously stated, includes a plate or wire shaped to represent a human head, the said head being surrounded by a ring member 11'. The ring member 11' is in turn surrounded by an outer ring member 12, the latter being provided with studs 13 having headed ends 14 to be received in the notches of the frame 1'. Between the rings 11' and 12 there are spacer bars 15, and certain of these spacer bars support thereon figures or letters 16. The figures or letters, as well as the ring members and the inner pattern 17 have their lower edges formed with pointed studs or pins 18 which project a slight but suitable distance below the widened lower edge of the frame 1'. This pattern is em-

ployed in a manner similar to that previously described.

The simplicity of my invention, and the advantages thereof will, it is thought, be perfectly apparent to those skilled in the art to which such devices relate when the foregoing description has been carefully read in connection with the accompanying drawings, so that further detailed explanation of the improvement is not believed necessary.

Having described the invention, I claim:—

A confectioner's pattern marker, including a frame whose lower edge is widened outwardly and whose upper edge is notched, partitions in the frame, said partitions having headed studs projecting from the outer ends to be received in the notches of the frame, said partitions having their upper edges notched, patterns having headed studs extending outwardly therefrom to be received in the notches of the frame and in the notches of the partitions, and each of said patterns having pins on the lower edges thereof which project through the frame.

In testimony whereof I affix my signature.

CARL MARCH.
